N. Y., A CORPORATION OF NEW YORK

PROCESS OF PREPARING LEUCO-1,4-DIHYDROXYANTHRAQUINONES

No Drawing.

Application filed November 20, 1929. Serial No. 408,664.

This invention relates to improvements in the process of preparing leuco-1,4-dihydroxyanthraquinones from 2-halogen (3-halogen)-1,4-dihydroxyanthraquinones. It relates particularly to improvements in the preparation of leuco-quinizarine from 2-chloro (3-chloro)-quinizarine.

An object of the present invention is to produce a leuco-1,4-dihydroxyanthraquinone (herein referred to as "a leuco-quinizarine") from a 2-halogen (3-halogen)-1,4-dihydroxyanthraquinone (herein referred to as "an ortho-halogen-quinizarine") by a process which requires only a relatively short period of time for its completion.

Another object of the invention is to provide a process for the production of a leuco-quinizarine by a reduction of an ortho-halogen-quinizarine in an alkaline medium.

Other objects of the invention will in part be obvious and will in part appear hereinafter.

It has been proposed to prepare leuco-quinizarine by heating 2-chloro (3-chloro)-1,4-dihydroxyanthraquinone (herein referred to as "chloroquinizarine") in solution in a sulfuric-boric acid mixture with a finely divided metal powder. It also has been proposed to prepare leuco-quinizarine from quinizarine (1,4-dihydroxyanthraquinone) by the action of a metal on quinizarine in an acid solution, by the action of alkaline hydrosulfite on quinizarine in an alkaline solution, and by the action of a finely divided metal and an organic acid on quinizarine in solution in an inert organic solvent. It is known, furthermore, to prepare leuco-quinizarine from purpurin [1,2,4 (1,3,4)-trihydroxyanthraquinone] by the action of a finely divided metal on purpurin in an acid, neutral, or slightly alkaline solution. The reduction of purpurin in alkaline solution by means of sodium amalgam, stannous salts, or alkaline hydrosulfite, however, does not produce leuco-quinizarine, but leads to the formation of xanthopurpurin (1,3-dihydroxyanthraquinone).

The preparation of leuco-quinizarine from chloroquinizarine by the action of a finely divided metal powder on a solution of chloro-

quinizarine in a sulfuric-boric acid mixture is objectionable, owing to the requirement of careful low temperature control, the relatively long period of time required for the completion of the reaction, and the foaming which occurs.

The invention accordingly comprises the several steps and the relation of one or more of such steps with respect to each of the others thereof, which will be exemplified in the process hereinafter disclosed, and the scope of the invention will be indicated in the claims.

We have discovered that a leuco-1,4-dihydroxyanthraquinone (a leuco-quinizarine) can be obtained from a 2-halogen (3-halogen)-1,4-dihydroxyanthraquinone (an ortho-halogen-quinizarine) by subjecting it to a reducing action in an alkaline medium, and the present invention comprises the application of this discovery to the preparation of a leuco-quinizarine from an ortho-halogen-quinizarine.

In the practice of the invention an ortho-halogen-quinizarine in solution or suspension in an alkaline medium may be heated with a reducing agent, for example, a hydrosulfite, until the reduction is complete. The solution may then be made acid with an acidic substance, or a salt may be added to it, whereupon a leuco-1,4-dihydroxyanthraquinone (a leuco-quinizarine) may be obtained as a precipitate. The precipitate may be filtered off, washed and dried. It may be further purified by recrystallization from a suitable solvent.

Among the halogen-quinizarines which may be treated in accordance with the invention, there are included the substituted and the unsubstituted 2-halogen (3-halogen)-1,4-dihydroxyanthraquinones; particularly the ortho-halogen-quinizarines which may be represented by the following formula:

in which x represents a halogen atom (such as chlorine, bromine, iodine, or fluorine).

as, -Clor-Br), A represents a hydrogen atom or a hydroxyl group, and B represents a hydrogen atom, a halogen atom, or a substituent radical, such as, -OH, -SO₃H, etc.; e. g., 2-chloro (3-chloro)-1,4-dihydroxyanthraquinone (chloro-quinizarine); 2-bromo (3-bromo)-1,4-dihydroxyanthraquinone (bromo-quinizarine); 2-chloro (3-chloro)-1,4,7,8-tetrahydroxyanthraquinone (chloroquininalizarine); bromoquininalizarine; 2-chloro-, or 2-bromo-, (3-chloro-, or 3-bromo)-1,4,5,8-tetrahydroxyanthraquinone; 2-chloro- or 2-bromo-, (3-chloro-, or 3-bromo)-1,4,5,8-tetrahydroxyanthraquinone-6-sulfonic acid; 2-chloro-, or 2-bromo-, -alizarine pentacyanine (1,4,5,7,8-pentahydroxyanthraquinone); etc. It is noted that when the halogen-quinizarine contains additional halogen or sulfonic acid substituents in the beta-position, these may also be replaced by hydrogen during the reaction. The alkaline medium is preferably a dilute solution of a caustic alkali, and may be used in excess of the amount required to form an alkali-metal salt of the halogen-quinizarine. The reducing agent, as for example, a hydrosulfite (e. g., sodium hydrosulfite), a stannous salt (e. g., sodium stannite), etc., is preferably employed in considerable excess in order to bring about a complete reduction.

When the step of acidifying the reduced solution is employed as a part of the procedure, any suitable acidic substance may be used, such as an acid or an acid salt; e. g., sulfuric acid, hydrochloric acid, sodium acid sulfate, sodium acid sulfite, etc. When the step of adding a salt to the solution is employed, any suitable salt which will salt out the leuco-quinizarine from its solution may be used; e. g., sodium sulfate, sodium chloride, etc. The procedure in which an acidic substance is added to the reduced solution is preferred, however; and the stronger acids are employed in preference to the weaker acid salts, inasmuch as they tend to leave a smaller amount of undehalogenated material in the final product.

If desired, the leuco-quinizarine may be oxidized directly to quinizarine without isolation from the reaction mixture, e. g., passing air through the mass upon completion of the reduction until the oxidation is complete, neutralizing with dilute acid, filtering off the quinizarine, washing and drying.

As an illustrative embodiment of a manner in which the invention may be carried into practice the following example is presented. The parts are by weight.

Example: 100 parts of 2-chloroquinizarine in the form of a paste is mixed with 7,000 parts of water, and 150 parts of sodium hydroxide in the form of a 50% aqueous solution is added with agitation. The mixture is heated to boiling, and when substantially all of the 2-chloroquinizarine has apparently

gone into solution, about 160 to 200 parts of sodium hydrosulfite (100% or its equivalent) is added. Reduction appears to take place immediately, the color of the solution changing from a deep bluish violet to bright yellow. Boiling is continued for about ten minutes to insure completion of the reaction, heating is then interrupted, and the mixture is added at once to about 300 parts of dilute sulfuric acid (50%). Leuco-quinizarine precipitates in the form of brownish-yellow granules. It is filtered off, washed acid-free with water, and dried. The crude product thus obtained is in the form of a yellow solid which, on analysis, shows a chlorine content of approximately 0.2 per cent. Upon recrystallizing from toluene or dichlorobenzene, a purified leuco-quinizarine melting at about 151° C. is obtained.

It will be evident that the invention is not limited to the details of the foregoing specific example, but that the process may be varied within wide limits without departing from the spirit and scope of the claims.

Thus, the invention is not limited to the treatment of chloroquinizarine but is generally applicable to the treatment of other ortho-halogen-quinizarines; i. e., 1,4-dihydroxyanthraquinone compounds which contain a halogen substituent in the 2-(3-) position. Other alkalis may be employed instead of sodium hydroxide, and the strength and amount may vary. It is desirable in practice, however, to employ at least sufficient alkali to form an alkali-metal salt of the chloroquinizarine. Instead of sodium hydrosulfite, other alkali-metal hydrosulfites or a mixture of substances which will generate hydrosulfite under the reaction conditions (such as, zinc and sodium bisulfite) may be employed. Furthermore, the hydrosulfite need not be added to the boiling alkaline solution of the chloroquinizarine, but they may be mixed at another point in the procedure; e. g., before the solution is heated. The reaction is preferably carried out at the boiling point of the solution, although other temperatures may be used.

Acidic substances other than sulfuric acid may be added to the reduction mixture to produce a precipitate of the leuco-quinizarine, e. g., hydrochloric acid, sodium bisulfite, sodium bisulfate, etc., or the leuco-quinizarine may be salted out from the reduction mixture by means of a suitable salt, such as, an alkali-metal sulfate, sulfite, chloride, etc.; e. g., sodium sulfate, sodium sulfite, sodium chloride, etc. By carrying out the reduction with an alkali-metal hydrosulfite and about sufficient alkali to form the alkali-metal salt of the chloroquinizarine, the leuco-quinizarine formed can be caused spontaneously to separate from the reaction mixture by the sodium bisulfite produced as a result of the reduction.

The present invention thus makes possible

the production of a leuco-quinizarine by an alkaline reduction of an ortho-halogen-quinizarine, and is superior to the process herefore known for the reduction of an ortho-halogen-quinizarine in that it does not require a long period of time for its completion, or careful low temperature control, and entails no difficulties from foaming.

Since, in carrying out the above process, 10 certain changes may be made without departing from the scope of the invention, it is intended that all matter contained in the above description shall be interpreted as illustrative and not in a limiting sense.

15 It is also to be understood that the following claims are intended to cover all of the generic and specific features of the invention herein described and all statements of the scope of the invention which, as a matter of 20 language, might be said to fall therebetween.

We claim:

1. The process of preparing a leuco-quinizarine which comprises reducing an ortho-halogen-quinizarine in an alkaline medium.
- 25 2. The process of preparing a leuco-quinizarine which comprises heating an ortho-halogen-quinizarine with a reducing agent in an alkaline medium.
3. The process of preparing a leuco-quinizarine which comprises reacting an ortho-halogen-quinizarine in an alkaline medium with a hydrosulfite.
- 30 4. The process of preparing a leuco-quinizarine which comprises reacting an ortho-halogen-quinizarine in an alkaline medium with a stannous salt.
5. The process of preparing a leuco-quinizarine which comprises heating an alkaline solution of an ortho-halogen-quinizarine with 40 an alkali-metal hydrosulfite.

6. The process of preparing a leuco-quinizarine which comprises reacting an ortho-halogen-quinizarine in an alkaline medium with a hydrosulfite, and acidifying the resulting reaction mixture.

7. The process of preparing a leuco-quinizarine which comprises reacting an ortho-halogen-quinizarine which corresponds with 50 the probable formula

55 in which x represents a halogen atom, A represents a hydrogen atom or a hydroxyl group, and B represents a hydrogen atom, a halogen atom, or an inorganic radical, in an alkaline medium with a hydro sulfite.

8. The process of preparing a leuco-quinizarine which comprises heating an alkaline 60 solution of an ortho-halogen-quinizarine

which corresponds with the probable formula

70

in which x represents a halogen atom, A represents a hydrogen atom or a hydroxyl group, 75 and B represents a hydrogen atom, a halogen atom, or an inorganic radical, with an alkali-metal hydrosulfite.

9. The process of preparing a leuco-quinizarine which comprises reacting an ortho-halogen-quinizarine which corresponds with 80 the probable formula:

85

in which x represents a halogen atom, A represents a hydrogen atom or a hydroxyl group, 90 and B represents a hydrogen atom, a halogen atom or an inorganic radical, in an aqueous caustic alkali solution, with an alkali-metal hydrosulfite, and treating the resulting reaction mixture with an acidic substance.

10. The process of preparing a leuco-quinizarine which comprises reacting an ortho-halogen-quinizarine which corresponds with 95 the probable formula:

100

in which x represents a halogen atom, A represents a hydrogen atom or a hydroxyl group, 105 and B represents a hydrogen atom, a halogen atom or an inorganic radical, in an aqueous caustic alkali solution, with a stannous salt, and treating the resulting reaction mixture with an acidic substance.

11. The process of preparing a leuco-quinizarine which comprises reducing chloro-quinizarine in an alkaline medium.

12. The process of preparing a leuco-quinizarine which comprises reducing chloro-quinizarine in an alkaline medium with a hydrosulfite.

13. The process of preparing leuco-quinizarine which comprises heating an aqueous caustic alkali solution of chloroquinizarine with sodium hydrosulfite.

14. The process which comprises heating an aqueous caustic alkali solution of chloro-quinizarine with sodium stannite, and acidifying the resulting reaction mixture, whereby leuco-quinizarine is produced.

15. The process of preparing leuco-qui-

110

115

120

125

130

nizarine which comprises heating an alkaline solution of chloroquinizarine with sodium hydrosulfite, and mixing the resulting reaction mixture with dilute sulfuric acid.

16. The process which comprises reducing an ortho-halogen-quinizarine in an alkaline medium, oxidizing the leuco-quinizarine thus formed directly to quinizarine, neutralizing, and separating the quinizarine.

17. The process which comprises reducing chloroquinizarine by heating in an alkaline medium with a hydrosulfite, oxidizing the leuco-quinizarine thus formed directly to quinizarine by means of air, neutralizing with a dilute acid, and separating the quinizarine.

18. The process which comprises heating to boiling in an alkaline medium an ortho-halogen-quinizarine and a hydrosulfite in the proportion corresponding to 100 parts of chloroquinizarine to about 160 to 200 parts of sodium hydrosulfite, and acidifying the reaction mixture, whereby leuco-quinizarine is produced.

19. The process which comprises heating 100 parts of 2-chloroquinizarine with at least 160 parts of sodium hydrosulfite in an excess of dilute aqueous caustic alkali solution until the change in color of the reaction mixture ceases, mixing an excess of an acidic substance with the resulting reaction mixture to render it acidic, and separating the leuco-quinizarine thereby produced.

20. The process which comprises admixing 100 parts of 2-chloroquinizarine in the form of a paste with 7000 parts of water, adding about 150 parts of sodium hydroxide in the form of an aqueous solution and heating to boiling until a solution is formed, then adding about 160 to 200 parts of sodium hydrosulfite, boiling to insure completion of the reaction, acidifying the reaction mixture with dilute sulfuric acid, and separating the leuco-quinizarine thereby produced.

21. The process of preparing a leuco-quinizarine which comprises reducing an ortho-halogen-quinizarine in an alkaline medium, and treating the resulting reaction mixture with an acidic substance.

22. The process of preparing a leuco-quinizarine which comprises heating an ortho-halogen-quinizarine with a reducing agent in an alkaline medium, and acidifying the resulting reaction mixture.

23. The process of preparing leuco-quinizarine which comprises heating an aqueous sodium hydroxide solution of 2-chloroquinizarine with sodium hydrosulfite, and acidifying the resulting reaction mixture with dilute sulfuric acid.

50. In witness whereof, we have hereunto set our hands.

JAMES OGILVIE.
DONALD G. ROGERS.
